INVENTOR

BY Victor J. Evans

ATTORNEY

WITNESS: John Donavan

UNITED STATES PATENT OFFICE

WILLIAM FRANKLIN WILMOT, OF DETROIT, MICHIGAN, ASSIGNOR OF ONE-HALF TO
LUCY B. WARNER, OF ALGONAC, MICHIGAN

MANICURE FILE

Application filed September 2, 1927. Serial No. 217,214.

This invention relates to a manicure file, the general object of the invention being to form the file with longitudinally extending gutters in which the filing surfaces are located so that the gutters act to hold the file on the nail and also to make the gutters of different depths so as to facilitate the uniform cutting of nails to any desired length.

Another object of the invention is to provide the file with a point at one end and a cutting edge at the other for operating on the cuticle at the base of the nail.

Another object of the invention is to provide the file with a gutter which is smooth 15 on its bottom so that this gutter can be used for smoothing the edge of a nail after the same has been cut and also to provide a flat part on the file, one side of which is smooth, the other side of which is formed with filing 20 surface, one edge of which flat part of file is formed with filing teeth for use in cutting and clearing out corners of nails.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view of the improved file.

Figure 2 is a view taken a quarter turn from Figure 1.

Figure 3 is a view of the opposite side of the file shown in Figure 1.

Figure 4 is a view of the opposite side from that shown in Figure 2.

Figure 5 is a section on line 5—5 of Figure 1.

As shown in these views, the file A is made 45 of round stock, or other desirable shaped stock, embodying the gutter method of a manicure file, with one end pointed, as shown at 1, and the other end tapered and formed with two flat sides, as shown at 2, this end 50 terminating in a beveled cutting edge 3.

Grooves 4 are formed in the body of the file and extend longitudinally thereof.

These grooves are of different depths and are formed with the file teeth on their bottoms, as shown at 6. One of the grooves 55 is left plain, as shown at 6', and the file teeth of the groove 6' extends over a flat surface of the point 2, as shown at 6'', so that these file teeth can be used for cutting the corners 60 of nails.

From the foregoing it will be seen that I have provided a file, the point 1 of which can be used for pushing back the cuticle, and the edge 3 for removing this cuticle. By providing grooves with the filed parts on their bottoms, the file is held against the nail being cut and by making the grooves of different depths, the nails can be cut to a uniform length by using the same groove for all of the nails. The plain groove without the 70 filed parts is used for smoothing the nails after being cut and the filed part 6'' can be used for cutting the corners of the nails.

It is thought from the foregoing description that the advantages and novel features 75 of my invention will be readily apparent.

I desire it to be understood that I may make changes in the construction and in the combination and arrangement of the several parts, provided that such changes fall within the scope of the appended claim.

What I claim is:

A manicure file comprising a body formed of round stock with one end pointed and the other end tapering and provided with two 85 flat sides and a sharp edge at its extremity, the body being formed with a plurality of grooves, which extend the length of the body and terminate in the tapered portions one groove being plain and the others having file 90 teeth in their bottoms, the teeth of one groove extending over a flat side of the tapered end of the file.

In testimony whereof I affix my signature.

WILLIAM FRANKLIN WILMOT. 95
